EX

OR D 14,015

Design No. 14,015, dated July 3, 1883.

UNITED STATES PATENT OFFICE.

WILLIAM R. BASSETT, OF NEW YORK, N. Y., ASSIGNOR TO SACKS & BROTHER, OF SAME PLACE.

DESIGN FOR A CURTAIN-LOOP.

SPECIFICATION forming part of Design No. 14,015, dated July 3, 1883.

Application filed April 19, 1883. Term of patent 7 years.

To all whom it may concern:

Be it known that I, WILLIAM R. BASSETT, of the city and State of New York, have invented a certain Design for Curtain-Loops, of which 5 the following is a specification.

This design relates to the curtain-loop having a certain artistic appearance in consequence of the peculiar construction.

My design is shown in the accompanying 10 drawing.

I make use of the ordinary cord, *a*, doubled and the ends brought together and inclosed by the ornamental band or ruff *b*. The ornamental tassel *c* is connected at the ruff or band 15 *b* by the small cords *d*.

In this design the tassel hangs loosely from the loop of stiff cord, and has a pleasing appearance that is different from the curtain-

loops heretofore made, because only one large tassel is used instead of two, and the ends of 20 the large cord of the curtain-loop are not visible, and the tassel and the ruff or band appear as one central ornament to the loop.

I claim as my invention—

The design of the curtain-loop, consisting in 35 the combination, with the central band or ruff around the large cords, of a tassel hanging from such band or ruff, substantially as described and shown.

Signed by me this 3d day of April, A. D. 30 1883.

WM. R. BASSETT.
